UNITED STATES PATENT OFFICE.

WILLIAM P. DIVINE AND ALBERT J. SHINN, OF PHILADELPHIA, PENNSYLVANIA, ASSIGNORS
TO DECKER ELECTRICAL MANUFACTURING COMPANY, A CORPORATION OF DELAWARE.

PRIMARY BATTERY.

No. 859,437.

Specification of Letters Patent.

Patented July 9, 1907.

Application filed August 1, 1906. Serial No. 328,649.

To all whom it may concern:

Be it known that we, WILLIAM P. DIVINE and ALBERT J. SHINN, both of Philadelphia, in the county of Philadelphia and State of Pennsylvania, have invented certain Improvements in Primary Batteries, of which the following is a specification.

This invention is a primary battery in which a series of porous tubes are supported and connected by a header or headers so that they form communicating compartments for the circulation of solution therein and contain elements immersed in a solution exterior to the tubes.

This construction and the further improvements comprised in the invention will more fully appear by reference to the following description and the accompanying drawings in illustration thereof.

In the drawings, Figure 1 represents a broken sectional side elevation of a cell made in accordance with our invention, Fig. 2 represents a plan view of the same, Fig. 3 represents a transverse vertical sectional view thereof, Fig. 4 represents a broken vertical sectional side elevation of a modified form of the invention, Fig. 5 represents a plan view of the form of the invention shown in Fig. 4, and Fig. 6 represents a transverse sectional view of the modified construction.

As shown in Figs. 1, 2, and 3 of the drawings, the envelop 1 has therein two sets of horizontally disposed porous tubes 2 with their respective ends set in the solid headers 3, preferably of graphite, and the hollow headers 4 of non-conducting material independent in construction from the envelop. The headers 4 provide conduits with which the respective sets of tubes communicate, and have at their bottoms the nipples 5 which are set in the conduit 6 supported on the bottom 35 of the envelop and having the nipple 7 which projects therethrough. Within the respective tubes 2 are the rod electrodes 8, preferably of graphite, set in the solid headers 3 by which they are supported, the rods being screw threaded and of irregular surface to engage them 40 in their supports and to increase the area of the exposed surfaces for the action of the battery solution contained in the tubes. Within the envelop on either side of the row of tubes are placed plate electrodes 9 and 9', preferably of zinc, subject to the action of a 45 solution introduced and withdrawn by way of the passage 7' through the bottom of the envelop. A terminal 10 connects the electrode headers 3 and a terminal 11 connects the electrodes 9 and 9'.

As shown in Figs. 4, 5, and 6, the envelop 12 has 50 therein the vertically disposed porous tubes 13 set in the horizontally disposed hollow headers 14 which are supported in the bottom of the envelop and provide a

common connection for the circulation of a fluid in the tubes. The headers 14 are provided with nipples 15 by which they communicate with a conduit 16 having a 55 nipple 17 passing through the bottom of the envelop. The conduit 16 and the block 18 resting on the bottom of the envelop support the headers 14.

Within the porous tubes 13 are disposed carbon electrodes 19 provided with screw threads 20 by which 60 they are connected to the conducting headers 21 which may be of sectional construction connected and supported by the conducting dowel screws or rods 22 passing through the envelop 12 and a terminal 23. Within the envelop and exterior to the porous tubes are the 65 zinc electrodes 24 provided with the dove-tail tops 25 which engage with the dove-tail grooves 26 of couplings 27 connected with the terminal 28.

Having described our invention, we claim:

1. A battery comprising an envelop, a hollow header 70 within said envelop and constructed independently thereof, a plurality of porous tubes connected by said header, a second header, and electrodes in said tubes connected by said second header.

2. A battery having a plurality of porous tubes, a hollow header connecting and supporting ends of said tubes, electrodes within said tubes, and a conducting header connecting and supporting said electrodes.

3. A battery having a plurality of porous tubes, electrodes within said tubes, a hollow header connecting and 80 supporting corresponding ends of said tubes, and a conducting header connecting and supporting corresponding ends of said electrodes and supporting corresponding ends of said tubes.

4. A battery having a plurality of porous tubes, electrodes within said tubes, a header electrically connecting and supporting said electrodes and closing corresponding ends of said tubes, a hollow header connecting the opposite ends of said tubes, a conduit with which said hollow header is connected, and an envelop in which said parts 90 are contained.

5. A battery comprising an envelop, a plurality of hollow headers within said envelop, a conduit with which said headers are connected, a plurality of sets of tubes each having corresponding ends thereof connected by one 95 of said hollow headers, a plurality of sets of electrodes each disposed in one of said tubes, and a conducting header for connecting each set of said electrodes.

6. A battery having an envelop, a hollow header therein, porous tubes connected by said header, threaded electrodes in said tubes, and a conducting header connecting said electrodes.

In testimony whereof we have hereunto set our names, this 27th day of July, 1906, in the presence of the subscribing witnesses,

WILLIAM P. DIVINE.
ALBERT J. SHINN.

Witnesses:

CHARLES P. ULM.
FRANK A. DECKER.
